UNITED STATES PATENT OFFICE.

ADOLPH MILLER, OF KIRKWOOD, MISSOURI.

TOWEL-CABINET.

1,387,932.

Specification of Letters Patent. Patented Aug. 16, 1921.

Application filed June 26, 1919. Serial No. 306,867.

To all whom it may concern:

Be it known that I, ADOLPH MILLER, a citizen of the United States, and a resident of Kirkwood, St. Louis county, Missouri, have 5 invented a new and useful Improvement in Towel-Cabinets, of which the following is a specification.

My invention relates to towel cabinets of the kind wherein a plurality of towels are 10 supported. It has for its objects to provide a simple means for keeping a clean towel constantly in position for use, for disposing of the used towels, for removing the dirty towels from the cabinet and replacing them 15 with clean towels and for preventing the loss or theft of towels.

The invention consists in a rotatable support for the towels and in the parts and combinations of parts hereinafter set forth 20 and claimed.

In the drawings, which constitute a part 25 of this specification and wherein like reference characters designate like parts in the several views,

Figure 1 is a plan view of my improved 30 towel cabinet showing a used towel and a clean towel in position to be used;

Fig. 2 is a vertical sectional view showing 35 clean and used towels in position and showing the construction of the rotatable towel support;

Fig. 3 is a top plan view showing the arrangement of the towels in the cabinet;

Fig. 4 is a plan view showing the arrangement 35 of the towels and the means for holding them in position before they are put in the cabinet;

Fig. 5 is a detail view of the towel supporting means; and

Fig. 6 is a view showing how the towels 40 are folded.

A cylindrical member 1 is rotatably secured to a base 2 by means of a bolt 3. The base 2 for said cylinder 1 is supported on a 45 pedestal 4. A washer 5 is interposed between the bottom of the cylinder 1 and the base 2. A ball bearing or other anti-friction bearing may be used if desired, and a ratchet member or the like may be added 50 permitting the cylinder to rotate in only one direction. A conical shell 6 has upwardly projecting clips 7 secured thereto. The clips 7 are adapted to receive a ring 8 on which towels 9 are mounted by means of 55 eyelets or gromets 10 in one corner thereof.

The shell 6 forms a seat for the towels. The

shell 6, clips 7 and ring 8 constitute the towel supporting means. The ring 8 is shown as having a plurality of notches 11 therein. The towels 9 are strung on the ring 8, the 60 gromets of the towels resting in the notches 11 of the ring. The meeting ends of the ring 8 are secured together by a padlock 12. Each towel is so folded that a portion 13 thereof projects over the ring 8, the body of 65 the towel resting on the support 6. The overhanging portion 13 is large enough to balance the towel and prevent it from sliding down inside the cylinder 1 under ordinary usage. The shell 6 may be made with 70 a bottom so as to make it impossible for the towels to drop down into said cylinder 1.

A cylindrical casing 14 having a dome-shaped top 15 is also mounted on the base 2. The casing 14 is larger than the cylinder 1, 75 so that there is room enough between them for towels to hang. The casing 14 is removably held by resilient fingers 16 secured to the base 2 and bearing against the casing 14. The casing 14 has a vertical opening 17 80 therein, and the dome 15 has a circular opening 18 alining with said opening 17. A towel is grasped through the opening in the dome and after being used is allowed to drop into the opening of the casing 14.

When the overhanging end 13 of a towel is pulled, the towel support is rotated slightly due to the fact that the eyelet or gromet 10 of the towel is held in one of the notches 11 of the ring 8. After the towel has 90 been used, it is allowed to drop down into the space between the support 1 and the casing 14. The rotation of the support has in the meantime brought a clean towel in position to be grasped through the opening in 95 the dome.

The towels are placed on the ring 8 and then folded as shown in Fig. 6. The towels are folded along the diagonal line $a-a$ passing through the gromet 10 and the opposite corner of the towel, then along the line $b-b$ parallel to the line $a-a$, then transversely along the line $c-c$ so as to leave the overhanging portion 13 above mentioned. When bundles of clean towels are being delivered, 100 a ring 20 rests on the towels to keep them in place, said ring having a diameter which is approximately the mean diameter of the conical support 6.

It will be understood that a different form 110 of ring or supporting member may be used, that the towels may be folded in a manner

different from that described, that the outer casing and dome may be different from those described and that other changes and modifications may be made without departing 5 from my invention.

What I claim is:

1. A towel cabinet comprising a base, a rotatable member secured thereto, a removable seat mounted on said rotatable member and 10 a retaining ring adapted to have towels strung thereon, said towels resting on said seat.
2. A towel cabinet comprising a rotatable towel supporting member and a retaining 15 ring for the towels secured thereto, said retaining ring having notches along its upper face, the towels having eyelets therein, said eyelets resting in the notches of said retaining ring, whereby a pull on a clean towel rotates the towel supporting member.
- 20 3. A towel cabinet comprising a base, a

rotatable member secured thereto, and a towel supporting member removably mounted on said rotatable member, said towel supporting member comprising a conical seat 25 for the towels and a retaining ring on which the towels are mounted.

4. In a towel cabinet, a conical shell in which the clean towels rest and a retaining ring secured above said conical shell, the 30 towels being mounted on said retaining ring.

5. In a towel cabinet, a conical seat for the towels, said seat being rotatably mounted, and a towel retaining member secured to 35 said towel seat, said retaining member comprising a ring having a plurality of notches in its upper face, said notches constituting positioning means for the towels mounted on said ring.

Signed at St. Louis, Missouri, this 11th 40 day of June, 1919.

ADOLPH MILLER.
